H. L. MOSES

CONFORMATOR FOR HATS

Filed Aug. 5, 1926

INVENTOR.

Herbert L. Moses
BY

Charles B. Mann, Jr.
ATTORNEY.

UNITED STATES PATENT OFFICE.

HERBERT L. MOSES, OF BALTIMORE, MARYLAND, ASSIGNOR TO M. S. LEVY AND SONS, INC., OF BALTIMORE, MARYLAND, A CORPORATION OF MARYLAND.

CONFORMATOR FOR HATS.

Application filed August 5, 1926. Serial No. 127,236.

This invention relates to a conformator attachment for hats and has for its object to provide a hat with a permanent flexible conformator of improved construction whereby 5 the hat may be made more comfortable for the wearer.

Another object of the invention is to provide an improved construction and arrangement of flexible conformator attachment for 10 hats whereby the hat may more comfortably fit the head and which will avoid undue pressure at any one place around the head.

The present invention is directly an improvement on the invention disclosed in 15 U. S. Letters Patent No. 1,362,343, granted December 14th, 1920, on an application for patent filed by me.

In my said patented structure, I employ 20 a flexible band which is interposed between the sweat-band and the interior crown wall which flexible band is held in a floating condition by stitches that pass through the said band at a point that is spaced from both the upper and lower edges of the flexible band.

That patented structure has proved a decided advance in conformators and meets the requirements up to a certain point, but its structure is such that it is held in place in 30 the hat by a single row of stitching centrally disposed between the upper and lower marginal edges of the band. This single row of stitching permits the band to have a freedom at its upper and lower edges and in 35 some instances it has been found that the lower edge would curl or turn up and produce a ridge at the outer side of the sweat-band which ridge becomes annoying to the wearer when the hat is worn.

40 My present invention therefore overcomes the difficulty referred to.

The invention is illustrated in the accompanying drawing, wherein,—

Fig. 1. shows a cross-sectional detail 45 through a hat the crown of which sustains my improved conformator attachment.

Fig. 2. illustrates on an enlarged scale a portion of a crown and brim with the improved device supported from the wall of 50 the crown and the relation of sweat-band with respect to the improved device, and

Fig. 3. shows an enlarged sectional plan through a portion of the crown.

Referring to the drawing the numeral 5, 55 designates the brim of a hat and 6, the

crown thereof. It is not essential to the invention whether the hat be of straw or felt as the invention is readily applicable to either.

On the interior of the crown 6 and near 60 the bottom thereof, I provide a flexible band 7 which latter is preferably, but not necessarily, formed of elastic material.

In my prior patent this band is shown as secured by a single row of stitching centrally disposed between the upper and lower marginal edges of the band, but in this present structure I secure the elastic band by rows of stitching 8 which rows are spaced apart and preferably parallel and engage the 70 band close to the upper and lower marginal edges 9 and 10 of the band.

The flexible band is of a smaller diameter than the diameter of the interior of the crown so that a space or gap 11 will be 75 formed on the interior of the crown between the latter and the band.

The spaced-apart rows of stitching 8 alone sustain the flexible band in that they extend from the latter across the gap or space 11 80 and pass through the crown wall and thereby ensure that the band throughout its entire width from its upper to its lower marginal edges will always remain in a plane parallel 85 with the crown wall and will not pucker or curl at its edges.

The rows of stitching 8 form upper and lower flexible suspension means between the crown and flexible band and are sufficiently spaced in a circumferential direction to allow the band to yield circumferentially.

The rows of suspension stitches extend horizontally and pass through the crown wall at points that will hold the flexible band in a slightly elevated position with respect 95 to the brim 5 of the hat.

The sweat-band 12 may be of any well-known form with or without ventilation means.

In the form shown, however, the sweat-band has a tape or edging 13, by which it is attached directly to the base of the crown by means of stitches 14 and from this attached point the sweat-band extends inwardly and curves at 15 beneath the lower edge 105 of the flexible band 7 and then turns upwardly at the inner side of said latter band.

The flexible band therefore keeps the sweat-band spaced from the crown wall and the plural rows of stitching 8, prevent said 110

flexible band from canting and maintains the curve 15 in the sweat-band where the latter passes around the lower edge of the flexible band, and prevents said lower edge from spreading outwardly or curling up as it frequently does if but a single central row of stitching is employed to secure the flexible band to the crown wall.

Having described my invention, I claim,—

10 1. A hat having a crown and a brim with a flexible band on the interior of the crown wall that is spaced from the latter, said flexible band being attached to the crown wall by plural rows of stitching that extend 15 across the space between said crown and band said rows of stitching holding the flexible band adjacent to both its upper and lower edges to prevent the same from canting and a sweat-band attached to the crown beneath 20 the flexible band and extending beneath and around the lower attached edge of the flex-

ible band and then upwardly at the inner side of the flexible band.

2. A hat having a crown and brim with a flexible band around the interior of but 25 spaced from the crown wall,—said flexible band being attached to the crown wall by upper and lower rows of marginal edge stitches that extend across the gap between said band and the crown wall said upper 30 and lower rows of stitching maintaining the upper and lower marginal edges of the band in a fixed spaced relation with respect to the crown wall and a sweat-band at the inner side of the flexible band and curving 35 outwardly beneath the lower secured edge of the flexible band and held in the curved condition by said lower flexible band-edge and the lowermost edge of the sweat-band being secured at the base of the crown. 40

In testimony whereof I affix my signature.

HERBERT L. MOSES.
